CLAIM

The ornamental design for a rectilinear pendant light fixture, as shown and described.

DESCRIPTION

FIG. 1 is a bottom perspective view of a rectilinear pendant light fixture including my design;

FIG. 2 is an enlarged bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing portions of the light fixture form no part of the claimed design. The rectilinear pendant light fixture is shown broken away down the center to indicate that the design has no specific length.
